UNITED STATES PATENT OFFICE

134,336

DESIGN FOR A SPRAYER PUMP HEAD

Harold V. Saffell, Los Angeles, Calif.

Application September 1, 1942, Serial No. 108,101

Term of patent 3½ years

To all whom it may concern:

Be it known that I, Harold V. Saffell, a citizen of the United States and residing at Los Angeles, in the County of Los Angeles and State of California, have invented a new, original, and ornamental Design for a Sprayer Pump Head, of which the following is a specification, reference being had to the accompanying drawing, forming part thereof, in which:

Fig. 1 is a front elevational view of the sprayer pump head showing my new design;

Fig. 2 is a side elevational view of the sprayer pump head;

Fig. 3 is a top view in perspective.

I claim:

The ornamental design for a sprayer pump head, substantially as shown.

HAROLD V. SAFFELL.
